SHOE CONSTRUCTION

Robert Stile and Philip Eisenberg, Brooklyn, N. Y.

Application December 21, 1944, Serial No. 569,162

4 Claims. (Cl. 36—11)

1

This invention relates to shoe construction and in particular to a type that is fundamentally adapted to provide comfortable wear both indoors and outdoors, and for sport as well as dress wear.

A particular object of the invention is to provide a shoe structure that lends itself to a simplified form of construction and on which can be made up in several different styles for different use under varying conditions. A still further object of the invention is to form a shoe structure from two pieces of material by so cutting and forming the body part of the pattern that it can be sewn into shape and provided with a top covering portion by the simple expedient of sewing along the edges of the parts to complete the shoe.

Our shoe is in the nature of a low cut foot covering and preferably made from a leather or simulation thereof that is provided with a soft inner face of down, hair, wool or other substance and so constructed that it will readily conform to the shape of the foot of the wearer and provide a cushioned support for the foot in walking.

With these and other objects in view, the invention comprises certain constructions herein-after described and then particularly pointed out in the claims, and a preferred embodiment of our invention is illustrated in the accompanying drawing, in which:

Figure 1 is a plan view of the pattern from which a shoe constructed in accordance with our invention may be made.

Figure 2 is a plan view of the pattern of the top piece which forms the vamp of the shoe.

Figure 3 is a rear view in elevation of a shoe constructed in accordance with our invention, the top edge being shown unturned at one side of the shoe.

Figure 4 is a view in side elevation of the shoe, the rear view of which is illustrated in Figure 3, part of the upper portion being also left unturned to show the construction.

Figure 5 is a modified form of construction made from two or more pieces forming the upper of the shoe.

Figure 6 is an enlarged section taken on the line 6—6 of Figure 5 showing the assembled edge structure of the shoe, and

Figure 7 is a plan view of a pattern of one half side of the upper of a shoe that is used in structures where further shaping of the shoe is desired.

Referring to the drawing in detail, 10 indicates a blank of leather or other suitable material hav-

ing an outer smooth surface and an inner lined or fleeced surface 11, the latter of which need not be used if the particular type of shoe does not call for it. The blank 10 presents a unitary structure providing a front part 12 and a back part 13. The edges of the blank at a point intermediate the front and back portions being cut obliquely as at 14 and outwardly from the edges of the front part 12 which is narrower than the back part 13. The forward edge of the front 12 is semi-circularly shaped as at 15 and provided with spaced gores or notches 16, which when sewn along their opposing edges pull the blank into shoe shape as shown in Figure 4, wherein the sewing of said notches 16 not only adds ornamentation to the front part of the shoe but also shapes the same. The sewing 17 of the notches meets a line of sewing 18 through the medium of which the top piece blank 19 is secured in place to complete the shoe structure and provide an extended tongue portion 20 as seen in Figure 4. The top piece 19 tapers in width from front to back and at opposite ends is rounded as at 21. The rounded front end will fit into the rounded front end of the sewn blank 10 and while a lace may be added for ornamentation, or to tighten the upper edge of the shoe about the foot, it is not deemed necessary to the invention. The shoe is completed by the sewing together as at 20 of the opposing edges of two rear gores or 25 notches 26 disposed at opposite sides of the median line of the blank 10 and in the rear edge thereof. This sewing also adds ornamentation to the shoe at the back thereof, the complete shaping of the shoe being accomplished by the sewing together of the rear edges 27 of the blank as at 28.

In the form of the invention shown in Figures 40 5 and 6, the shoe is of more substantial construction, made so by applying a sole and solid heel. The upper of the shoe, as indicated as at 30, is shaped by the sewing 31 and along the lower edge thereof has stitched thereto as at 32 a ribbon or 45 binding strip, which is turned as at 33 to conceal the stitching and to have its free edge 34 glued or cemented as at 35 to the underside of a felt or other filler sole 36, which at the back of the shoe is likewise secured to the upper surface of a wood 50 heel piece 37. The strip 32 is cemented to the bottom surface of the wood piece 37 as by the cement zone 38, but is otherwise attached to the felt sole member 36. This strip holds the upper in shape and gives rigidity to the lower portion 55 of the shoe structure, as it extends all around

the shoe and also gives a unique appearance to the shoe.

The shoe body is cemented to the upper surface of the inner sole 36 as by cement illustrated at 40, and the shoe is finished by a bottom sole 41 secured in any suitable manner as by cementing to the underside of the wood heel piece 37 and the filler sole 36 and strip 32. While the shoe structure illustrated in Figures 3 and 4 may be employed as the upper of the shoe shown in Figure 5, we may also make the shoe from two upper side pieces 45, as shown in Figure 7, which are united by sewing at the front and rear edges as at 46 and 47 respectively and be provided with sew lines 48 at the front side portions thereof as at 49. In this instance the bottom of the shoe 50 would be separately sewn along the edges to the side pieces 45 as at 51. Either form of the structure may be employed as deemed desirable according to the needs. For instance, the shoe structure of Figure 4 may be used in sport shoes that do not require right and lefts, while the separate bottom structure may be used in shoes for dress wear, or for size fittings. The combination of inner fleeced bottom surface with the felt inner sole 36 and soft fibrous outer sole 41 gives a comfortable cushioning effect and provides adequate support for the foot in walking. The extended side edges of the back part 13 constitute the turned over cuff portions 52 of the shoe.

Our invention is not to be restricted to the precise details of construction shown since various changes and modifications may be made therein without departing from the scope of the invention or sacrificing the advantages derived from its use.

What we claim is:

1. A shoe fabricated from a blank consisting of a semi-circular front edge having several substantially uniformly spaced V-shaped notches therein, the side edges of said blank flaring towards the back, said flaring starting at approximately that part of the blank which when the shoe is fully formed is in the region of the instep, the back edge of the blank having a pair of V-shaped notches one to either side of the center of said back edge, the side edges of each of said notches being stitched together whereby to draw up the blank into the shape of a shoe having a sole, sides, front and back portions in a unitary structure, and a top piece for closing the shoe-formed-shape at the upper front thereof and completing the shoe structure, said top piece being sewed to the forward portion of the shoe around the free edges thereof, said flared edge portions extending from the instep to the back of the shoe and being adapted to be turned over to form a cuff.

2. A shoe fabricated from a blank consisting of a semi-circular front edge having several substantially uniformly spaced V-shaped notches therein, the side edges of said blank flaring towards the back, said flaring starting at approximately that part of the blank which when the shoe is fully formed is in the region of the instep, the back edge of the blank having a pair of V-shaped notches one to either side of the center of said back edge, the side edges of each of said notches being stitched together whereby to draw up the blank into the shape of a shoe having a sole, sides, front and back portions in a unitary

structure, a top piece for closing the shoe-formed-shape at the upper front thereof and completing the shoe structure, said top piece being sewed to the forward portion of the shoe around the free edges thereof, said flared edge portions extending from the instep to the back of the shoe and being adapted to be turned over to form a cuff, and a separate sole portion secured to the sole of the shoe.

- 10 3. A shoe fabricated from a blank consisting of a semi-circular front edge having several substantially uniformly spaced V-shaped notches therein, the side edges of said blank flaring towards the back, said flaring starting at approximately that part of the blank which when the shoe is fully formed is in the region of the instep, the back edge of the blank having a pair of V-shaped notches one to either side of the center of said back edge, the side edges of each of said notches being stitched together whereby to draw up the blank into the shape of a shoe having a sole, sides, front and back portions in a unitary structure, a top piece for closing the shoe-formed-shape at the upper front thereof and completing the shoe structure, said top piece being sewed to the forward portion of the shoe around the free edges thereof, said flared edge portions extending from the instep to the back of the shoe and being adapted to be turned over to form a cuff,
- 15 20 25 30 35 40 45 50 55 60 65 70 75 80 85 90 95 100
4. A shoe fabricated from a blank consisting of a semi-circular front edge having several substantially uniformly spaced V-shaped notches therein, the side edges of said blank flaring towards the back, said flaring starting at approximately that part of the blank which when the shoe is fully formed is in the region of the instep, the back edge of the blank having a pair of V-shaped notches one to either side of the center of said back edge, the side edges of each of said notches being stitched together whereby to draw up the blank into the shape of a shoe having a sole, sides, front and back portions in a unitary structure, a top piece for closing the shoe-formed-shape at the upper front thereof and completing the shoe structure, said top piece being sewed to the forward portion of the shoe around the free edges thereof, said flared edge portions extending from the instep to the back of the shoe and being adapted to be turned over to form a cuff, a separate sole portion secured to the sole of the shoe, a strip attached to said blank and engaging said sole portion to hold the two in structural relationship, and an outer sole beneath said sole portion and secured to said strip.
4. A shoe fabricated from a blank consisting of a semi-circular front edge having several substantially uniformly spaced V-shaped notches therein, the side edges of said blank flaring towards the back, said flaring starting at approximately that part of the blank which when the shoe is fully formed is in the region of the instep, the back edge of the blank having a pair of V-shaped notches one to either side of the center of said back edge, the side edges of each of said notches being stitched together whereby to draw up the blank into the shape of a shoe having a sole, sides, front and back portions in a unitary structure, a top piece for closing the shoe-formed-shape at the upper front thereof and completing the shoe structure, said top piece being sewed to the forward portion of the shoe around the free edges thereof, said flared edge portions extending from the instep to the back of the shoe and being adapted to be turned over to form a cuff, a separate sole portion secured to the sole of the shoe, and an outer sole beneath said sole portion and secured thereto.
